UNITED STATES PATENT OFFICE.

HARRY E. EHRENFELD, OF BALTIMORE, MARYLAND.

STATION INDICATOR.

Application filed May 27, 1924. Serial No. 716,284.

To all whom it may concern:

Be it known that I, HARRY E. EHRENFELD, a citizen of the United States, residing at Baltimore, in the city of Baltimore 5 and State of Maryland, have invented certain new and useful Improvements in Station Indicators; and I do hereby declare the following to be a full, clear, and exact description of the invention, such as will 10 enable others skilled in the art to which it appertains to make and use the same.

This invention relates to improvements in a station or street indicator, adapted for use upon railway conveyances and has 15 for its object the provision of a device of this character, whereby the operator of the railway conveyance can readily announce the names of the approaching stations or streets to the occupants of the conveyance 20 so that they will at all times be aware of their exact location.

Another object of this invention is the provision of a casing having a sight opening adapted to have moved in register therewith, names of streets or stations occurring along the line of travel of the conveyance and as the conveyance approaches the respective streets or stations, the name thereof will be visible through the sight 25 opening so that the occupants of the conveyance may readily determine the name of the next approaching street or station.

A further object of this invention is the provision of a ribbon or apron having names 30 of streets or stations occurring along the line of travel of the conveyance printed or otherwise applied thereon and which apron or ribbon is mounted upon a pair of relatively spaced rollers adapted to be 35 wound from one roller to the other and passed in rear of the sight opening of the casing so that the names of the streets or stations may be viewed by the occupants 40 of the conveyance as the respective streets or stations are approached.

A further object of this invention is the provision of a novel form of operating means located in convenient reach of the operator of the conveyance and so connected with the belt or ribbon supporting 45 drum that they can be actuated in either direction so that the device can be operated to move the names of the streets or stations in view through the sight opening in the casing.

A still further object of this invention

is the provision of a street or station indicator of the above stated character, which is simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a side elevation of a street or station indicator applied to a fragmentary portion of a railway conveyance shown 75 in vertical section,

Figure 2 is a front elevation of the device,

Figure 3 is a transverse sectional view taken on the line 3—3 of Figure 2, illustrating means for operating the ribbon or belt in either direction,

Figure 4 is a transverse sectional view taken on the line 4—4 of Figure 2,

Figure 5 is a vertical sectional view of 85 the device taken on the line 5—5 of Figure 4,

Figure 6 is a detail view illustrating the end of the ribbon or belt supporting rollers,

Figure 7 is a transverse sectional view taken on the line 7—7 of Figure 6,

Figure 8 is a fragmentary sectional view taken on the line 8—8 of Figure 3, illustrating specifically the means for reversing 95 the operation of the device,

Figure 9 is a detail view partly in section taken on the line 9—9 of Figure 1,

Figure 10 is a detail sectional view taken on the line 10—10 of Figure 5, illustrating 100 the means for preventing reverse operation and which will permit of reverse operation of the device when desired,

Figure 11 is a detail sectional view taken on the line 11—11 of Figure 5,

Figure 12 is a detail view illustrating a portion of the operating means,

Figure 13 is a plan view partly in section of a ratchet controlling lever.

Referring in detail to the drawings, the numeral 1 indicates a substantially cylindrical casing, which is adapted to be se-

cured at any convenient point, within a railway conveyance 2, preferably at one end adjacent the top thereof as shown in Figure 1. The substantially cylindrical casing 1 is provided with an offset housing 3 for the purpose of receiving a master gear and drive shaft, which will be hereinafter more fully described.

The casing 1 at a point opposite the offset housing or portion 3 is provided with an opening, which extends the entire width of the casing and has the edges of the walls thereof so bent as to form guide flanges 4. The guide flanges 4 are adapted to slidably receive a closure slide 6. One end wall of the casing 1 is of a greater height than the other, at the point of the opening as shown at 7 for the purpose of forming a stop. The closure slide 6 is adapted to be inserted within the guides 4 from one end of the casing and abuts the stop 7. The closure slide 6 is provided with a sight opening closed by a glass panel 8, whereby names of stations and streets moved in rear of the sight opening may be viewed by the occupants of the conveyance.

A frame consisting of inner and outer plates 9 and 10 is located in one end of the casing 1 and the outer plate is provided with suitable brackets, which are secured to the walls of the casing 1 by fasteners 11. The inner and outer plates 9 and 10 are relatively spaced and have journaled therein, upper and lower stub shafts 12, which stub shafts extend through the plates of the frame. A similar frame 13 is located in the other end of the casing 1 and secured therein, in a manner similar to the before described frame and has journaled therein, the upper and lower stub shafts 12. The inner ends of the stub shafts 12 are provided with reduced squared extensions 14, which cooperate with squared reduced ends 15 upon ribbon or belt supporting shafts 16, which extend across the casing 1 in spaced relation thereto. The shafts 16 are provided with screwthreaded apertures adjacent each end thereof for the purpose of receiving screws 17. The reduced extensions 14 and 15 of the stub shafts 12 and ribbon or supporting shafts 16 are held together by a substantially U-shaped spring clasp 18, as shown in Figure 7, whereby the shafts 16 may be readily detached from the stub shafts 12 when desired, and later removed from the casing 1 by way of the opening thereof by removing the slide or closure 6.

A ribbon or belt 19 has its ends secured to the shafts 16 by plates 20 which are secured to the shafts over the ends of the ribbon or belt, by the screws or fasteners 17, whereby the belt or ribbon may be removed and replaced upon the shafts 16 when desired. The ribbon or belt 19 has printed or otherwise applied thereon in spaced rela-

tion, names of streets or stations occurring along the route or line of travel of the railway conveyance. The ribbon or belt 19 is adapted to be wound from one shaft 16 to the other shaft and when moving from one shaft to the other, it passes over guide rollers 21 journaled to the casing 1 adjacent the sight opening so that the names of the streets and stations will be disposed rearwardly of the glass panel 8. The stub shafts 12 journaled in the frame that is constructed from the plates 9 and 10 have secured thereon gears 22 and 23, respectively, and which gears are connected by an intermediate gear 24 carried by the wall or plate 9 so that the shafts 16 are compelled to rotate in the same direction. The stub shafts 12 that are journaled in the frame 13 have secured thereon gears 25 and 26 respectively, which gears are connected by an intermediate gear 27 journaled to the inner plate of the frame 13. Slidable stub shafts 28 and 29 are mounted within the frame 13 adjacent the stub shafts 12, and have secured thereon reversing gears 30 and 31 respectively. The reversing gears 30 and 31 are normally urged in mesh with the gear 25 and the intermediate gear 27 by springs 32. The outer ends of the stub shafts 28 and 29 project through the end wall of the casing 1 adjacent ears 33 carried by the casing. The ears 33 have pivoted thereto, reversing levers 34 and 35 which are each provided with cam faces 36 adapted to engage the ends of the slidable stub shafts 28 and 29, whereby when the reversing levers are in substantially horizontal position, they permit the reversing gears 30 and 31 to mesh with the gears 25 and 27 under the influence of the springs 32. By swinging the levers 34 to a substantially vertical position, the cam faces 36 force the stub shafts 28 and 29 to slide against the tension of the springs 32, disengaging the reversing gears thereon from engagement with the gears 25 and 27; owing to the cam faces 36 upon the reversing levers 34 and 35, they will normally remain either in substantially vertical position or a horizontal position so as to either hold the reversing gears in operative or inoperative position.

An operating shaft 37 is journaled in the offset portion 3 of the casing 1 and has secured to one end thereof, a master gear 38 which is adapted to mesh with either of the reversing gears 30 or 31 according to which gear occupies an operative position. The outer end of the operating shaft 37 extends exteriorly of the casing and is squared, having secured thereto a curved arm 39. The curved arm 39 has pivotally secured thereto a rod 40, which extends downwardly through the flooring 41 of the car and is slidably connected to a bell-crank lever 42. The bell crank lever 42 is pivoted

to a bracket 43 carried by the flooring 41 of the car. A rod 44 is pivoted to the bell crank lever 42 and extends forwardly, having a universal joint 45 on its forward end 5 to which is connected an arm 46. The arm 46 is pivoted to an arm 47 carried by a vertical rod 48. The vertical rod 48 extends through the flooring 41 of the conveyance 2 and through the supporting brackets 49 10 carried by the front of the conveyance. The upper end of the vertical rod 48 is squared to receive a controller handle 50. The controller handle 50 has a hand grip 54 carrying a spring pressed pin 55 adapted to extend through an aperture in the supporting plate 49 to hold the controller handle in a normally non-operating position. The supporting plate 49 has secured thereto, a lug 56 for limiting the movement of the controller handle upon its operative stroke.

The curved arm 39 heretofore referred to as secured to the squared end of shaft 37 has a body portion 51 in which is rotatably mounted a ratchet wheel 52, 53 indicating a 25 spring pawl that engages said ratchet wheel 52 to insure rotation thereof in one direction only.

A ratchet wheel 56 is secured to the uppermost stub shaft 12 adjacent the gear 22 and 30 is adapted to be engaged by a pair of spring actuated dogs 57, which are pivotally connected to the member 58 carried by the shaft 59. The shaft 59 is journaled in one end wall of the casing 1 and has secured 35 thereto a controlling lever 60. The controlling lever 60 has a hand grip 61 provided with a spring pressed pin adapted to engage within either of a pair of relatively spaced apertures formed in one end wall of the casing 40 so that either one of the dogs 57 may be held in engagement with the ratchet wheel 56 so as to hold the device against reverse rotation when operating in one direction upon the line of travel of the conveyance 2.

45 A plurality of relatively spaced fingers 62 are formed upon the operating shaft 37 and are adapted to rock an arm 63 upon its pivot 64. The arm 63 extends exteriorly of the casing by way of a slot 65 and has 50 formed upon its outer end a ball or sphere 66 adapted to hit a gong or bell 67 carried by the casing 1, so that upon movement of the operating shaft 37 to operate the device, the gong or bell 63 will be sounded, attracting 55 the attention of the occupants of the conveyance to the device. The inner end of the arm 63 is held in close relation to the fingers 62 by a spring 68.

In operation, when the conveyance is approaching a street or station, the operator 60 of the conveyance swings the controller handle 54 in the arc of a circle against the stop 56, rotating the shaft 48, which actuates the rod 40 through the bell crank lever 42 and 65 rod 44. Upon movement of the rod 40 up-

wardly, the shaft 37 is turned. One of the reversing gears 30 or 31 is in mesh with the master gear 38 and either the gear 25 or intermediate gear 27, the ribbon or belt is so moved to cause the name of the 70 respective station or street to appear behind the glass panel 8. Upon the name of the street or station appearing behind the glass panel 8, the gong 67 is actuated by the fingers 62 rocking the arm 63 upon its pivot, 75 thus attracting the attention of the occupants of the conveyance to the device. After the conveyance has reached its terminal and desires to return, the reversing gears 30 or 31 are moved in the opposite direction by 80 the reversing levers 34 and 35 so that one reversing gear meshes with the master gear 38 while the other reversing gear is in an inoperative position. The controlling handle 60 is so turned as to disengage one dog 85 57 from engagement with the ratchet wheel and permits the other dog to engage the same to prevent the reverse rotation of the ribbon or belt when the controlling lever 54 is returning to its normal position after 90 moving upon an operative stroke.

One of the stub shafts 12 extends exteriorly of the casing 1 and has secured thereto, a crank handle 71, whereby the shafts 16 may be turned in either direction for operating the device or for resetting the apron, providing the same is not operating correctly to cause the names upon the apron to agree with the approaching streets or 95 stations. 100

What is claimed is:

A station indicator comprising a casing having a sight opening, frames secured within the ends of the casing, stub shafts journaled in said frames and having reduced 105 ends, apron shafts having reduced ends engaging the reduced ends of the stub shafts, U-shaped clamps detachably connecting the reduced ends of said shafts, an apron bearing characters carried by said apron shafts and movable from one of said last named shafts to the other in rear of the sight opening, trains of gears connecting the stub shafts and located within the frames, a drive gear in the casing, reversing gears rotatably 110 and slidably mounted in one of the frames and adapted to connect the gears of one of the trains to the drive gear, means for controlling the reversing gears, and a reversible ratchet mechanism associated with one of the 115 stub shafts to prevent reverse operation of the device when operating in either direction. 120

In testimony whereof I affix my signature in presence of two witnesses.

HARRY E. EHRENFELD.
